UNITED STATES PATENT OFFICE.

WALTER F. SABEL, OF EVANSVILLE, INDIANA, ASSIGNOR OF ONE-HALF TO HARRY J. SABEL, OF EVANSVILLE, INDIANA.

SHIPPING-CASE AND BASKET CONSTRUCTION.

1,358,581.

Specification of Letters Patent.

Patented Nov. 9, 1920.

Application filed March 24, 1920. Serial No. 368,349.

To all whom it may concern:

Be it known that I, WALTER F. SABEL, a citizen of the United States, residing at Evansville, in the county of Vanderburgh and State of Indiana, have invented a new and useful Shipping-Case and Basket Construction, of which the following is a specification.

This invention relates to the construction 10 of containers, particularly shipping cases and baskets.

The objects of the invention are to provide a strong, durable and sanitary construction in containers of various types, one 15 which will give good service under abuse and which may be readily manufactured. It is a further object to provide a container constructed almost wholly of wood but reinforced at the parts of greatest wear by metallic strips.

The preferred embodiment of the present invention comprises essentially end frames, side frames and a bottom frame united together. Each frame is preferably rectangular and has a webbing of interlaced strips of wood. The frames proper are protected at the points subjected to greatest wear by tin plate or similar reinforcement. The corners of the container are reinforced within 25 by vertical strips, while the outside of the corners are protected by triangular metallic corner plates. The construction is one of great strength as well as lightness and is specially useful when employed for making 30 shipping cases for bakeries and laundries. The same container, however, may be used as a truck by attaching wheels to the bottom of the same. This construction is also useful in making bakers' trays, delivery baskets 35 for groceries, waste baskets and many other articles. Many similar baskets employ wire for reinforcing the wood, but in the present construction no wire is used.

The invention will be best understood 45 from a consideration of the following detailed description taken in connection with the accompanying drawing forming part of this specification, with the understanding, however, that the invention is not confined to 50 any strict conformity with the showing in the drawing, but may be changed and modified so long as such changes and modifications mark no material departure from the

salient features of the invention as expressed in the appended claims. 55

In the drawing Figure 1 is a perspective view of a basket, or shipping case, constructed in accordance with the invention.

Fig. 2 is a top plan view of the same, portions of the reinforcing being broken away 60 to show the wood work construction.

Fig. 3 is a bottom plan view with portions of the reinforcing broken away to show the frame beneath.

Fig. 4 is a fragmentary view in elevation 65 of one of the ends, parts at the corners being broken away to show the construction more clearly.

Fig. 5 is a fragmentary view in vertical section looking toward one end of the container from the inside thereof. 70

Fig. 6 is a detail in perspective of one of the corner reinforcements.

The numeral 10 refers to the upper rails 75 of the end frames, said rails having at their ends a mortise and tenon joint 11 with the vertical stiles 12 of the end frames. A lower rail 14 having a mortise and tenon joint 13 with the stiles completes the frame work of the ends. A webbing of veneer or wood 80 strips interlaced with each other is secured upon the end frame. This webbing comprises straight vertical strips 16 and horizontal strips 15 woven in and out between the vertical strips, as clearly shown in Fig. 85 1. The ends of these horizontal strips 15 are united in any desirable way to the inside face of the stiles 12. The vertical strips are held to the frame by means of a lower strip 18 and the upper strip 17. Nails or any 90 other desirable fastening means are used to secure the webbing upon its frame.

The ends of the basket, which have just been described are placed between the sides of the same so as to lie flush with the ends 95 of the frame work of the sides. The sides comprise longitudinal lower rails 23 and upper rails 21; the same being secured at their ends by the mortise and tenon joints 22 and 20 respectively to upright corner 100 rails 19. The rails 21 and 23 form a rectangular frame work, and secured to this frame work is a web exactly like the webbing of the ends of the container. The webbing of the sides 105 comprises horizontal woven strips 27 and

vertical straight or unbent strips 26. The ends of the horizontal strips 27 are interposed between the corner sills 19 and the end frame sills 12, as seen in Figs. 1 and 4. 5 The vertical strips 26 are secured to the frames of the container sides by horizontal strips 24 and 25. The upper strip 24 runs longitudinally with the rail 21, and is spaced from the same only by the thickness 10 of the vertical strips 26. The lower longitudinal strip 25 runs likewise with the lower rail 23. These longitudinal strips 24 and 25 are similar to the strips 17 and 18 of the end frame. Nails or similar means 15 hold these longitudinal strips 17, 18, 24 and 25 to the frame work proper, such nails being passed through the ends of the vertical strips 16 or 26, as the case may be. From what has been said it is seen that the ends 20 and sides of the container may be built up completely and then assembled to form the container, the ends and sides being essentially separate units.

The bottom of the container as seen in 25 Fig. 3 includes the rails 32 and 30, which are mortised and tenoned together as at 31 forming a rectangular frame, and a longitudinal rail 34. Rail 34 is intermediate the rails 32 and secured to the short rails 30 by a mortise and tenon joint 31, similar to the joints previously mentioned. The longitudinal rail 34 prevents the bottom of 30 the crate or basket from bulging outwardly with a heavy load, and protects the same 35 from wear as well as rough handling. A webbing is secured to the bottom frame work and comprises straight cross strips 35, and woven or bent longitudinal strips 36. The cross strips 35 are secured upon the 40 longitudinal rails 32 and interposed between the same and the longitudinal rails 23 of the side frame work. The woven strips 36 are interposed between the strips 18 and rails 14 and the side rails 30 of the bottom frame 45 work.

Uprights 28, triangular in cross section, are secured to the inside of the basket at the corners thereof. These uprights 28 not only aid in holding the sides and ends together thus contributing to the strength of 50 the basket but keep the moisture and dirt away from the corners and make the basket a more sanitary one. Nails or similar elements 29 will be driven through these uprights 28 into engagement with the frame and webbing and will hold the parts in proper position.

The rails 21 and longitudinal strips 24 are inclosed on two sides by a metallic reinforcing, which may be of tin plate, and which has a cross section similar to an inverted U, as seen in Fig. 5. This reinforcing 55 37 protects the outside, inside and tops of the upper rail of the sides and ends of the container. The lower rails 14 and 23

are protected by a similar metallic reinforcement which, in this case, is L-shaped in cross section, as seen from Fig. 5. This L-shaped reinforcing 38 protects the outside and bottom of the lower rails of the sides 70 and ends of the container.

The reinforcing strips 37 and 38 run the entire length of the rails which they are designed to protect and are secured at the corners of the container by corner pieces 75 or irons 40 (see Fig. 6). These corner pieces may be made from tin plate or from any other form of metal and comprise two arms 41 and 42, which may be or may not be equal in length, said arms being flat 80 throughout and at right angles to each other. These arms have triangular shaped overlapping portions 44 and 45 which are secured to each other by a rivet 46, or a similar element. Perforations 43 may be 85 formed in the corner irons 40 before they are secured to the container, or these perforations might be made as the nails, or other fastening means 47 are driven in place. The corner irons for the upper and 90 lower corners are precisely the same except that the lower corner irons 40^a may have their arms of a greater width than the arms of the upper corner irons 40 to correspond with the width of the L-shaped protecting 95 strips 38. Elements 48 are driven through the arms of the corner irons and through the protecting strips 37 and 38, as the case may be, the rails receiving such elements. The reinforcing strips are thus held securely 100 to the frame work of the sides and ends of the container, while the corners of the container are doubly reinforced. Since the corners are the parts of the container subject to the greatest wear the necessity for this 105 construction will be appreciated.

The above described construction may be modified by fastening a lid to one edge thereof with hinges, and by providing a padlock, or the like for such a lid. Handles 110 might also be provided on the ends of the container so that it may be more easily moved about. The container is very strong and yet is light and sanitary. The metallic reinforcements protect the wood where it 115 would be likely to wear away while at the same time not adding materially to the weight of the container. The manufacture of such a container is attended with no difficulties and it requires no special skill to 120 repair the container or replace worn parts.

What is claimed is:

1. In a container the combination of sides, ends and a bottom each comprising a frame and webbing secured upon the frame, said webbing including straight strips and bent strips woven at right angles to the straight strips, the ends of the bent strips of the sides of the container being interposed between the side and end frames, other strips 130

secured to and running with the frames and holding the straight strips of the webbing to the frames, and uprights secured to the inside of the container at the corners thereof 5 and united to the frames and webbing.

2. In a container having sides, ends and a bottom each having a rectangular frame, said ends being received between the sides and the bottom being wholly below the ends 10 and sides, the combination therewith of a metallic reinforcing secured to the upper edges of the container, said reinforcing being of inverted U-shape and protecting the inside and outside of the top frame 15 members as well as the top thereof, a second metallic L-shaped reinforcing for the bottom frame members and protecting the bottom and outside of the same, and corner angle pieces each protecting a corner of the 20 container on three faces of the container and serving to hold the said reinforcing in place.

3. In a container having sides, ends and a bottom, means for reinforcing and protecting the upper and lower edges of the container and means for protecting the corners of the container, said latter means also holding the reinforcing means in place, the corner protecting means comprising an angular piece having arms at right angles, overlapped triangular strips each integral with 25 one of the arms and bent at right angles to 30

that arm, and means for uniting the overlapping strips.

4. A container comprising two end frames, two side frames and a bottom frame, 35 each constituting separate units, the end frames each comprising upper and lower rails with vertical stiles mortised and tenoned together and having a webbing of interlaced vertical and horizontal wood strips 40 secured thereto, the ends of the horizontal strips being secured to the vertical stiles, and the ends of the vertical strips being secured by upper and lower horizontal strips to the upper and lower rails, the side 45 frames comprising corner sills and top and bottom rails mortised and tenoned together and having a webbing of interlaced vertical and horizontal wood strips secured thereto, the ends of the horizontal strips of the side 50 frames being interposed between the corner sills and the end frame stiles while the vertical strips of the side frames are secured to the top and bottom rails by upper and lower horizontal strips, and the bottom frame in- 55 cluding side and end rails mortised and tenoned together and having cross strips and longitudinal strips interlaced together.

In testimony, that I claim the foregoing as my own, I have hereto affixed my signature.

WALTER F. SABEL.
